(57) **CLAIM**

The ornamental design for a cabinet handle and base, as shown and described.

DESCRIPTION

FIG. 1 is a perspective exploded view of a cabinet handle with base showing my new design including a handle part and a base part;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines shown represent unclaimed subject matter and form no part of the claimed design.
